US0D1054054S

(12) **United States Design Patent** (10) Patent No.: **US D1,054,054 S**
(45) Date of Patent: **** Dec. 10, 2024**

(54) **PIPETTE**

(71) Applicant: **Eppendorf SE**, Hamburg (DE)

(72) Inventor: **Verena Michel**, Hamburg (DE)

(**) Term: **15 Years**

(21) Appl. No.: **35/518,322**

(22) Filed: **Apr. 13, 2023**

(80) **Hague Agreement Data**

Int. Filing Date: **Apr. 13, 2023**

Int. Reg. No.: **DM/228388**

Int. Reg. Date: **Apr. 13, 2023**

Int. Reg. Pub. Date: **Sep. 15, 2023**

(51) **LOC (14) Cl.** **24-02**

(52) **U.S. Cl.**

USPC **D24/222**

(58) **Field of Classification Search**

USPC D24/216, 222-226, 231, 232
CPC B65D 25/108; B01L 9/543; B01L 3/0217;
B01L 3/0279

See application file for complete search history.
